COMBINED TYPEWRITING AND COMPUTING MACHINE

Henry L. Pitman, Hartford, Conn., assignor to
 Underwood Elliott Fisher Company, New York,
 N. Y., a corporation of Delaware

Application June 22, 1939, Serial No. 280,537

6 Claims. (Cl. 235—130)

This invention relates to combined typewriting and computing machines in which a general operator is power cycled to actuate reciprocatory computing wheel drivers after the latter have become indexed through operation of typewriter numeral keys, and in which the selection of the drivers to be indexed is under control of the typewriter carriage. The carriage may automatically initiate a power cycle of a general operator, and it may also automatically determine additive or subtractive states of the computing mechanism. Therefore, the carriage traverses and operates control mechanism at one or more computing zones within the range of carriage travel in letter feed or tabulating direction.

More particularly, the invention deals with key-locking mechanism, general-operator cycling mechanism, and carriage-return mechanism, and provides for coordination of these mechanisms one with the other and with other features of the machine.

In prior machines the keys, such as the numeral type keys, become locked through a camming operation which gets under way only as a cycle of movement of the general-operator-actuated mechanisms gets under way. Thus, after closing a clutch to start the cycle, there is an appreciable interval before the cycle has gotten under way sufficiently to effect full operation of the key-locking mechanism. Similarly, a cam operation has been employed to open the key-locking mechanism at the end of the cycle and hence there obtained an appreciable time interval between the unlocking of the keys and the end of all movement of the parts cycled by the general operator.

An object of the invention is to provide means whereby the keys become locked before the parts that operate in the cycle can start to move; and a further object is to provide means whereby the unlocking of the keys does not take place before the movement of the cycle-operated parts is suitably concluded. For such purposes a feature of the invention resides in having the mere closing of the clutch operative to actuate the key-locking mechanism to lock the keys; and, conversely, another feature is in having any key, in its operated position, prevent the closing of the clutch.

Another object of the invention is to provide relatively operative yet simple means for effecting coordination of the key-locking mechanism and cycling mechanism and to coordinate such means with a cycling key mechanism, a credit-

balance key mechanism and a power-operable carriage-return mechanism to the end of promoting efficient operation of these mechanisms and rendering them foolproof.

5 In respect to the carriage-return mechanism, certain computing-mechanism-control devices, ordinarily traversed by the carriage, are rendered inoperative concomitantly with initiating a power return of the carriage. By initiating a 10 return of the carriage, a cycle of the general operator is also initiated, the general operator mechanism being adapted to restore said control devices during a final portion of the cycle.

Means are employed whereby the cycle may 15 be effected in two stages in order that the final one of these stages, in which said control devices are restored, may be held up so as not to occur until the carriage has been fully returned. An electric motor, for operating the general 20 operator mechanism, may normally be at rest and therefore, when initiating a cycle, a switch is closed concomitantly to start the motor. Such motor tends to race when its load is subnormal. A two stage cycle, as above referred to, may also 25 be used as a single cycle device in conjunction with a manually operable cycling key in that depression of the cycling key effects only the first stage of the cycle and the concluding or cycle-completing stage is effected only by restoration of the key. The motor may be under sub-normal load when the general operator is merely cycled in response to a depression of the cycling key. A further object of the invention, therefore, is to provide for opening the motor 30 circuit at the end of the first stage of the cycle and for reclosing the motor circuit concomitantly with initiating the second stage of the cycle. Thus if the cycling key should be kept depressed after the first stage of the cycle is concluded, the motor current will have become cut off and racing of the motor cannot occur.

Other features and advantages will hereinafter appear.

This application is a continuation-in-part of 45 divisional subject-matter of my co-pending application, filed August 1, 1936, now Patent No. 2,178,702, dated November 7, 1939.

In the accompanying drawings:

Figure 1 is a side elevation view of the clutch 50 and dog mechanism.

Figure 2 is a cross sectional side elevation of a combined typewriting and computing machine including mechanism embodying the invention.

Figure 3 is a perspective of mechanism embodying the invention.

Figure 4 is a side view of motor switch contact mechanism.

Figure 5 is a side elevation showing the operation of parts of the key-locking mechanism.

Figure 6 is a rear elevation of the clutch and motor switch mechanism and includes a diagram of the motor circuit.

Figure 7 is a side elevation showing the relative positions of the parts of the clutch mechanism when the cycle has been arrested by the secondary dog device.

Figure 8 is a side elevation showing the operation of the clear-sign printing mechanism relatively to the cycling clutch mechanism.

Referring now more particularly to the drawings, a typewriter unit T surmounts a computing base B. Type actions including numeral-key levers 15 and corresponding type bars 18, are operable to print against a revolvable platen 19 mounted in a letter-feeding carriage 20 guided upon front and rear rails of the typewriter frame. The type actions, through a universal bar 24, actuate escapement dogs 25 relative to an escapement wheel, not shown, having a pinion 26 engaging a letter-feed rack 27 on the carriage. A spring motor 29 partly shown, Figure 2, urges the carriage in letter-feed and tabulating direction. Denominational tabulating key levers 30 may elevate corresponding denominational stop reeds 31 for interception by a tabulating stop 32 on a column unit 33 located on racks 34, 35 carried by the carriage 20. The elevation of any tabulating reed 31 actuates a universal bar 36 and its shaft 37 so that the latter through known connections, not shown, disengages the letter-feed rack 27 from the escapement pinion 26.

At the depression of any numeral key-lever 15, a rod 39 pendent therefrom rocks a shaft 40 to depress a corresponding digit bar 41 to depress a corresponding index pin 42 in a computing wheel driver or register bar 43. There are a digit bar 41 and a rock shaft 40, for each digit from "0" to "9" and these are part of the usual unit 44 of pin-setting linkages.

The computing base B may have one or more registers each comprising a set of computing pinions 45 and a corresponding set of the register bars 43 whose racks 46 mesh constantly with corresponding idlers 47. The register bars 43 normally stand with their digit pins 42 slightly to the rear and thus out of the path of descent of the corresponding digit bars 41. The register bars 43 of a selected register are advanceable seriatim in denominational order to bring their pins 42 under the digit bars 41 for the indexing operation.

A single set of denominational jacks 48 serves for advancing the register bars 43 of any one set to pin-setting position. Cam plates 49 are selectively depressible to connect corresponding sets of register bars to said single set of jacks 48. Cross blades 50 corresponding to the set of jacks extend laterally to the different sets of the register bars 43 which are distributed across the machine. A set of thrust rods 51 abuts the set of jacks 48 and is connected by a set of bell cranks 53, fulcrumed on a rod 54, to a set of master racks 55 connected to said cross blades 50. The latter in turn are connected to sets of distributive racks 52 corresponding to the sets of register bars and having couplers 56 pivoted to their forward ends. A set of the register bars 43 is selected for indexing by raising the companion set of couplers 56 from the normal depressed position, Figure 2, to a position in which the front ends of the couplers

are opposite rollers 57 on the register bars. A set of couplers is raised to effective position by depressing the corresponding cam plate 49, and the connections for this purpose include levers 58 on a fulcrum rod 59. Said connections further include a plate 60 and a thrust rod 61 for each cam-plate 49 so that depression of a cam plate 49 effects clockwise (Figure 2) rocking of a corresponding lever 58.

The fulcrum rod 59 is supported by side links 62 depending from horizontal arms 64 fixed to a rock shaft 65. Vertical arms 66 also fixed to said rock shaft 65 support the fulcrum rod 54 for the bell cranks 53. Also fixed to said rock shaft 65 is a latch plate 68 controlled by a latch arm 69 having a yieldable connection 70 to a rock shaft 71 journaled in the framework. By rocking the latching shaft 71 clockwise, Figure 2, its arm 69 is withdrawn from a step of the latch plate 68 whereupon the latter and its shaft 65 may rock clockwise until a second step of the latch plate 68 stops on the arm 69. Thus the thrust rods 51 and 61 may correspondingly drop. It follows that the set of denominational jacks 48 and cam plates 49 may also drop so as to be inoperative by the column units 33 on the typewriter carriage, each unit having a denomination-selecting tooth 72 and one or more cam-plate depressing tappets 73 for traversing and normally actuating said jacks and cam plates.

A register bar actuating cross bar 74 is connected to racks 75 mounted at the sides of the computing base B. A cross shaft 76 is connected by gearing, not shown, to both racks 75 so that the latter move in unison for reciprocating the cross bar 74. In its forward stroke the cross bar 74 engages the index pins 42 that have been set in its path and thereby advances the appropriate register bars 43 for turning the computing pinions 45. The return stroke of the cross bar 74 restores the register bars 43.

A cycling shaft 77, journaled in the framework, has a crank and pitman connection, not shown, to one of the racks 75 so that a full revolution of said shaft 77 reciprocates the cross bar 74.

When a set of couplers 56 is elevated to effective position by depression of the corresponding cam plate 49, a latch link 78 is withdrawn from a state-controller bar 79 so that the latter, urged 50 forwardly by a spring 80 assumes an additive position. There is a state-controller bar 79 for each register and its shift to additive position determines, through mechanism not shown, that the corresponding set of computing wheels will be 55 shifted, during the cycle, into and out of mesh with the register bar racks 46. Depression of a subtraction cam plate 82 operates through a plate, like 60, a thrust rod, like 61, and further connections, not shown, to rock a shaft 83 counterclockwise to withdraw secondary latches 84 so that any state-controller bar 79, that has been released to additive position, may move farther forward to subtractive position to determine that the corresponding set of computing pinions 45 will be 60 shifted into and out of mesh with the idlers 47 during the cycle.

After the last jack 48 has been actuated by the carriage in a computing zone, a cycling tooth 88 on the column unit 33 passes over and thus will 70 have rocked, within a letter feed step of the carriage, a lever 89 having a connection 90 to a cycling jack, the lower end of which abuts a thrust rod 91 partly shown at Figure 3. Said thrust rod 91 is connected to a bell crank 92, on the fulcrum rod 54. Said bell crank 92 abuts

an arm 93 yoked to an arm 94 which abuts a pin of an arm 85 fixed to a clutch trip rock shaft 96 journaled in the framework. The yoked arms 93, 94 are supported rotatably loose on a key-lock rock shaft 97 journaled in the framework.

A clutch dog 95 is fixed to the rock shaft 96 and normally engages a latch stud 98 of a plate 99 that, when released, is urged by a spring 81 to rotate limitedly clockwise, Figure 8, relatively to a plate 100. The plates 99, 100 have pin-and-slot connections 86 which limit the rotation of plate 99 relatively to plate 100. Said plate 100 carries spring-pressed clutch pawls 101 and is fixed to the cycling shaft 77. A toothed wheel 102 is normally rotatably loose on the cycling shaft 77 and has a worm-and-gear connection 103, Figure 6, to a shaft 104 that is drivable by a motor represented at M. The toothed wheel 102 is articulated at 102^a to a hub 103^a of the worm-gear of said connection. When the plate 99 is latched and restrained by the clutch dog 95, it holds the pawls 101 disengaged from the toothed wheel 102 by means of pawl-controlling pins 87 provided on plate 99, Figure 8. But when the plate 99 is released, through retraction of the clutch dog 95, the resulting slight clockwise spring-urged rotation of said plate 99 and corresponding recession of the pins 87 permits the pawls 101 to be moved by their springs 101^a, Figure 6, to engage the toothed wheel 102 which thus becomes clutched to and may rotate the cycling shaft 77. Before a revolution of the shaft 77 is completed, the clutch dog 95 will be ready to intercept the latch stud 98 to stop the plate 99 again. The pawl-carrying plate 100 continues to rotate limitedly ahead of the stop plate 99 thereby causing the pawls 101 to become disengaged from the toothed drive wheel 102 and stopping the cycling shaft 77 at the end of one revolution which will have completely effected a cycle of the rest of the general operator mechanism including the cross bar 74. The machine as thus far described is substantially as in my co-pending application, Serial No. 72,348, filed April 2, 1936, now Patent No. 2,160,487.

The pendent rod 39 of each numeral key lever 15 has a shoulder so that a thereabove portion of the rod 39 may enter between two of a series of lock rods 106 upon depression of the numeral key lever 15. Said rods 106 are confined, for limited spread, in a channeled cross bar 107 supported by the framework. Said cross bar 107 is suitably cross-slotted to admit and guide the pendent key lever rods 39. A lever 108 pivoted to the bar 107 has a tongue 109 normally clear of but enterable downwardly between two adjacent lock rods 106.

For each set of computing pinions 45, there is a push bar 110 carrying a clear sign key 111. Through mechanism, not shown, depression of said push bar 110 is blocked unless all of the corresponding set of computing pinions 45 stand at zero. In the latter case, the push bar 110 may be depressed and may thereby rock an arm 112 counterclockwise, Figure 8, against the pull of a restoring spring 113. Said arm 112 has a one-way driving connection 114 to an arm 115 fixed to a rock shaft 116 journaled in the framework. A latch arm 117 fixed to said rock shaft 116 normally is under a stud 125 on a link 118 which is forked to straddle the rock shaft 116 and which is pivoted to a lever 119 loosely fulcrumed on a rod 120 supported by the framework. A sleeve 121 yokes said lever 119 to an arm 122 having a link connection 123 to a lever 124 that is similar

to the numeral key lever 15 and is connected to one of the type bars 18. This one type bar has a clear sign printing type.

By depressing the clear sign key 111 to the Figure 8 position, its push bar 110 rocks the arm 112, and hence the rock shaft 116 and latch arm 117 counterclockwise, to the Figure 8 position. Said latch arm 117, thus rocked, frees the link 118 and hence frees the lever 119 and its companion arm 122 for counterclockwise rotation, about the rod 120, to the Figure 8 position (full line) by a spring 126. Said spring 126 thus urges the lever 124 downwardly to actuate the clear sign printing type bar to print against the platen 19; and a cycle of the general operator mechanism is concomitantly initiated for effecting restoration of the parts as follows. Through a suitable connection, not shown, the reciprocation of one of the general operator racks 75 is converted into a full clockwise revolution of a cam shaft 128, Figure 2, journaled in the computing base. During the latter part of the revolution of said shaft 128, a cam 129 fixed thereon engages a roll 130 of the lever 119 and thereby rocks said lever clockwise to restore the clear sign printing type bar and concomitantly raise the link 118 so that the latter becomes upheld by the latch arm 117 since the latter, urged by a spring 127, tends to return clockwise to normal position. Except for the connections whereby the described operation of the clear sign printing mechanism is attended by initiation of a general operator cycle and which connections will be described later, the clear sign printing mechanism and its operation as above set forth are substantially as in the Hart U. S. Patent No. 1,190,287.

A carriage-return shaft 105, Figure 2, has a driving connection, not shown, from the same motor M that drives the cycling shaft 77. A trip-link 131, when released, is moved rearwardly by spring 132 and through connections, including rock shafts 133, 134, moves a clutch-toothed pinion 135 along said shaft 105 into engagement with clutch teeth, not shown, on said shaft. Said pinion 135 meshes with a rack 136 on the carriage. Carriage-return-initiating release of the trip-link 131 may be effected manually by a key-lever 137 having a link-tripping arm 138. A tappet 139 on the carriage may engage a laterally adjustable cam arm 140 splined to a rock shaft 141. Said shaft is thus rockable clockwise, Figure 2, and is effective, through linkage 142, to restore the pinion 135, the rock shafts 133, 134 and the trip link 131 to shut off the power drive of the carriage at the end of a carriage return run. Carriage returning initiating release of the trip link 131 may also be effected automatically by the carriage at a line end through a connection 144 Figure 2. The carriage-return mechanism thus far briefly described is substantially as involved in my aforesaid copending application, Serial No. 93,820, now Patent No. 2,178,702.

The description will now proceed more particularly with reference to the present invention.

It will be remembered that a cycle is initiated by retracting the clutch dog 95 from the latch stud 98 of the plate 99 of the clutch mechanism. Said dog 95 has an extension 146 engaging a pin of an arm 147 fixed to the key-lock rock shaft 97 which has also fixed thereto another arm 148 having a link connection 149 to a bell crank 150 fulcrumed on the rod 120. An arm 151 of said bell crank is operatively connected with a companion arm of the key-locking lever 108.

Thus retraction of the cycling dog 95 results immediately in clockwise rotation, Figure 3, of the lever 108 to lock the numeral key levers 15 against effective operation. Conversely, the tongue 109 of the lever 108 cannot be entered into the series of lock rods 106 while a numeral key lever 15 is depressed and in that instance, therefore, the clutch dog 95 cannot be retracted to start a cycle. In other words, the register bars cannot be cycled by the general operator mechanism while a numeral key lever 15 and its corresponding unit bar 41 are depressed and engaged in setting a register-bar index pin 42.

The clutch dog 95 has a lock edge 153 under which the latch stud 98 passes when its plate 99 is released and is moved by its spring slightly clockwise of Figure 3. This blocks the retracted cycling dog 95 against restoration so that through the connections 146—151 the keys are kept locked until the cycle of the shaft 77 is well under way. As a cycle gets under way and before the latch stud 98 leaves the clutch dog's lock edge 153, the locking of the keys is taken over by the following devices. The key lock shaft 97 has fixed thereto an arm 155 connected by a link 156 to a lever 157 pivoted at 158 on the framework. Normally a roll 154 of said lever 157 occupies a recess 159 in the circular edge of a disk 160 fixed to the cycling shaft 77. When the cycle gets under way and the disk 160 becomes rotated so that its circular edge opposes the lever 157, the latter and said disk edge cooperate to keep the shaft 97 rocked in key locking position independently of the clutch dog 95. The latter may therefore resume its normal position for eventually intercepting the latch stud 98 for ending the cycle.

At the end of the cycle or revolution of the shaft 77 and its disk 160, the recess 159 will be in normal position to permit the arm 155 to rotate counterclockwise, Figure 3, to normal position under the urge of a spring 162 so as to unlock the keys. Said spring 162 may be applied, Figure 3, to the lock lever 108, and a co-operative spring 161, Figure 5, may be applied to the lever 157.

The unlocking of the keys is timed independently of the disk 160 so that it may occur only when all the parts actuated by the general operator have substantially resumed their normal positions. To this end means are involved as follows. As the general operator cross bar 74 nears the end of its return stroke, it engages a hook 163, Figure 2, on a link 164 pivoted to an arm 165 fixed to a rock shaft 166 having arms 167 connected by links 168 to a restorer bar 169 for the state control bars 79. The last portion of the return stroke of the cross bar 74 is thus accompanied by rearward movement of said restorer bar 169 to restore the state control bars 79, the latter having studs 170 engageable by said restorer bar. As the general operator racks 75 reach their fully returned positions, a spring-urged lever 171 pivoted on the framework and partly shown at Figure 2 drops abruptly into a notch 172 of one of the racks 75. Said lever 171 thus serves, through its sudden drop and through means, not shown, to depress the rear end of the link 164 and thereby disengage the latter from the cross bar 74 whereupon a spring 173 returns the link 164 and restorer bar 169 forwardly to normal positions. This restoring mechanism for the state control bars 79 is substantially as shown in my U. S. Patent No. 2,118,860 which also describes the operation of such mechanism to restore the index pins 42.

In the present machine, a key lock control bar 174 is slotted, Figure 8, for slidable support on headed studs 175 in the framework. Said bar 174 is urged rearwardly by a spring 176 that is not strong enough to overcome the restorer-bar spring 173 but sufficiently strong to make said key-lock control bar 174 follow the rearward movement of said restorer bar 169, said bar 174 having an upturned forward end 177 engaging the front edge of the restorer bar 169. Thus the key-lock control bar 174 moves limitedly rearward at the initial portion of the rearward stroke of the restorer bar 169 and thereby the rear end of said key-lock control bar 174 takes under an extension 178 of the lever 157 while the latter is maintained in key-locking position by the disk 160 as shown in Figure 5. Thus, said lever 157 is maintained in key-locking position until the bar 174 is moved forwardly again by restoration of the state control restorer bar 169 at the end of the return movement of the general operator cross bar 74 and thus substantially at the extreme end of the cycle. In effect, therefore, the general operator cross bar 74 and the hook link 164 cooperate as a latch device trippable by means of the lever 171 at the end of the cycle to release the restorer bar 169 and the consequent retraction of the key-lock control bar 174 releases in turn the lever key-lock lever 157 for restoration by its spring 161. Thus, the key-levers 15 will have remained locked until the restorer bar 169 has become restored. Therefore, no key-lever 15 and its companion unit bar 41 may be operated to set an index-pin 42 until the cycle has been fully completed and the machine is consequently in assuredly proper condition for pin setting. The lever 157 may be stopped in normal position by abutment of an arm 179 thereof with a stop 180 on the framework.

Operations of the described clear-sign printing mechanism, key-locking mechanism and cycling mechanism are coordinated as follows. It will be remembered that the depression of the clear-sign-key-carrying push bar 110 to the Figure 8 position rocks the shaft 116 counterclockwise to retract the latch-arm 117 to render the spring 126 effective to rock the lever 119 counterclockwise in a clear-sign-printing stroke. Depression of said push bar 110 is immediately effective to lock the numeral-key levers 15 in that there is fixed to the rock shaft 116 an arm 181 connected to an upright rod 182 guided at its upper end, as in the cross bar 107, for entry between two of the lock rods 106. The lever 119 has an arm 183 for engaging a stud of an arm 184 of a lever 185 pivoted on the framework. A stud of another arm 186 of said lever 185 engages the forward end of a thrust rod 187 that extends toward the cycle trip rock shaft 96 and is slotted so as to be slidable longitudinally on studs 188 on the framework. The rear end of said thrust rod 187 engages a stud 189 of an arm 190 that in itself is rotatably loose on said rock shaft 96 but is connected by a spring 191 to an arm 192 fixed to said rock shaft 96. The stud 189 extends through a slot 193 in the arm 192 and tends to be moved into abutment with the forward end of said slot by the spring 191 which thus maintains a yieldable connection between the arms 190, 192. This yieldable connection is for the following purpose. When the clear-sign-key-push bar 110 is depressed to the Figure 8 position, the concomitant entry of the rod 182 into the series of lock rods 106 imme-

diately closes the latter. This blocks the entry of the tongue 109 of the lever 108 into the series of lock rods 106 as is ordinarily effected by retraction of the cycling dog 95. Nevertheless, the clear-sign-printing stroke or counterclockwise rocking of the lever 119 may take place and be attended by rearward movement of the thrust rod 187 to turn the arm 190 counterclockwise on the clutch-dog rock shaft 96, and in that instance the spring 191 will merely yield and be tensioned since retraction of the clutch dog 95 is blocked by the closed lock rods 106. The spring 191 remains tensioned and therefore potentially effective to retract the clutch dog 95 inasmuch as the lever 119 remains rocked to its Figure 8 full-line position until a cycle of the machine is effected. When the push bar 110 is released, and is restored to its normal position by means of the spring 113, the key-locking rod 182 is withdrawn and this permits the tensioned spring 191 to retract the clutch dog 95 since the tongue 109 may now enter the series of lock rods 106. The numeral key-levers 15 may thus be locked from the time the push bar 110 is depressed until the cycle for restoring the rocked lever 119 and its related parts is completed.

The relation of the carriage-return mechanism, the key-locking mechanism, the mechanism for disabling the carriage control of the computing mechanism, and the cycling mechanism will now be described.

While the carriage is being returned, the numeral-key levers 15 are to be locked against operation and the carriage control of the computing mechanism is also to be disabled. It will be remembered that when the trip-link 131 is released for initiating a carriage return, the rock shaft 133 is rocked. Said shaft 133, when thus rocked, turns in counterclockwise direction of Figure 2. An arm 195 fixed to said rock shaft 133 is connected by a link 196 to a bell crank 197 fulcrumed on the framework. A link 198 connects said bell crank 197 to an arm 199 fixed to the rock shaft 71 in the computing base. Thus when the shaft 133 is rocked counterclockwise concomitantly with initiating a return of the carriage, the link 198 is depressed to rock the shaft 71 clockwise and thereby withdraw the latch arm 69 on the latter from the plate 68 so that the shaft 65 may rock clockwise to effect disablement of the carriage-control parts such as the jacks 48, the cam plates 49, 82, and the cycle trip lever 89, it being remembered that these parts are maintained in operative condition when the plate 68 is latched in its normal position as in Figure 2.

Inasmuch as a cycle of the shaft 71 is necessary to eventually restore these parts to normal position, a cycle is initiated concomitantly with release of the carriage-return trip link 131; and the accompanying drop of the link 198 may be employed to initiate the cycle through the following devices. A rock shaft 200 is journaled in the computing base and has fixed thereto an arm 201 having a pin 202 entered in a companion slot in a coupling plate 203 pivoted to an arm 205 that in itself is rotatably loose on the rock shaft 71. A spring 194, Figure 3, may connect the link 198 and the arm 201. Said arm 205 is normally positioned so that a recess 206 of said plate 203 articulates the latter to a pin 207 of the link 198. Said plate 203 thus serves as a disconnectible coupling between the link 198 and the arm 201 of the rock shaft 200. By shifting the arm 205 clockwise of Figure 3 and hence moving the plate

203 to the rear, as by setting a non-add key, not shown, an enlargement 208 of the recess 206 becomes positioned so that the plate 203 clears the link pin 207 and thus operatively disconnects the link 198 from the rock-shaft arm 201. However, with the plate 203 in normal position, Figure 3, the depression of the link 198 through initiation of a carriage return rocks the plate 203 downwardly which rocks the shaft 200 counterclockwise of Figure 3 so that an arm 209 fixed to said rock shaft 200 and connected by a link 210 to an arm 211 fixed to the clutch-trip shaft 96 rocks the latter counterclockwise of Figure 3 to retract the clutch dog 95.

15 In a long carriage-return run, as where a long carriage is employed, an ordinary full cycle of the shaft 71 would be completed before the carriage-return run is completed and therefore the computing mechanism controls such as the jacks 48, cam plates 49, 82 and cycling lever 89 would be restored and would be operable by the returning carriage before the completion of the carriage-return run. The restoration of these controls is effected during the last fourth or fifth portion of the revolution of the shaft 71. Therefore, the following means are employed to delay the last portion of said revolution or cycle and effect it only in response to completion of the carriage return so that operation of the controls by the returning carriage is prevented. When the rock shaft 200 is turned counterclockwise, at the initiation of a carriage-return operation, a secondary clutch dog 212 fixed to said shaft is interposed into the path of a stud 213 on the plate 99 of the clutch mechanism. The stud 213 is at a greater distance from the center of the plate 99 than is the stud 98 so that the latter may pass the secondary clutch dog 212. Moreover, the stud 213 is short enough so that it does not extend into the plane of the primary clutch dog 95 and thus will not be intercepted by the latter.

25 It will be apparent now that a cycle that is initiated concomitantly with initiation of a carriage-return operation will be interrupted when the interposed secondary dog 212 intercepts, as in Figure 7, the stud 213. This stops the plate 99 and hence, through the ensuing slightly farther rotation of the shaft 71 and its clutch-pawl carrying plate 100, the clutch pawls 101 are disengaged from the driving wheel 102. The parts are arranged so that when the cycle is thus interrupted, the shaft 71 will have turned from, say, three-fourths to four-fifths of its complete revolution.

30 35 The cycle remains interrupted until the carriage return is completed. It will be remembered that the carriage at the completion of its return rocks the shaft 141, Figure 2, clockwise. The shaft 133 is concomitantly rocked clockwise so that its connections with the secondary-clutch-dog shaft 200 permits the latter to rock clockwise under the urge of a spring 214, Figure 2. This retracts the secondary dog 212 from the stud 213 thereby permitting the spring-urged plate 99 to turn slightly clockwise relatively to the clutch-pawl carrying plate 100 so that the clutch pawls 101 reengage the drive wheel 102 for consequent resumption of rotation of the shaft 71. Concomitantly with the described retraction of the secondary clutch dog 212, the primary clutch dog 95 is restored for intercepting the stud 98 to reopen the clutch and stop the resumed rotation of the shaft 71 when the latter has completed its final one-fourth or fifth part of a complete revolution.

40 45 50 55 60 65 70 75

During said final part of a revolution of the shaft 71, a cam stud or roll 215 mounted on a disk 216 fixed to said shaft 71 works against a flange 217 of the latch plate 68 thereby turning the latter and its rock shaft 65 counterclockwise to the normal Figure 2 position in which said plate 68 becomes upheld by the latch arm 69 again. The restoration of the rock shaft 65 restores the fulcrum rods 54, 59 to their normal Figure 2 positions and consequently the carriage-controlled parts such as the jacks 48, cam plates 49, 82, and cycle-trip lever 69 are rendered operable by the carriage again.

The link 198 may be extended upwardly above the bell crank 197 that is associated with the carriage-return mechanism so that said link may also be operable by a bell crank 219 fixed to the universal shaft 37 associated with the tabulating-stop reeds 31. Said link 198 may have a pin-and-slot connection 220 to each of the bell cranks 197, 219 so that it may be depressed by either bell crank independently of the other. It will be apparent that depression of the link 198 through operation of the tabulating bell crank 219 has the same result as described with reference to operation of the carriage-return controlled bell crank 197. Thus, at depression of any tabulating-key lever 30, the carriage-actuated controls such as 48, 49, 82, 89 are disabled and a cycle is initiated to eventually restore said controls. The cycle is interrupted by the secondary dog 212 and is completed only upon release of the operated tabulating key 30.

A manually operable cycling-key lever 221, fulcrumed on the framework, is operatively connected as at 222, Figure 3, to an arm 223 connected by a sleeve 224 to the lever 185. Thus, depression of said key lever 221 rocks the lever 185 counterclockwise and the latter, through the thrust rod 187, rocks the clutch-trip rock shaft 96 to retract the primary clutch-dog 95 to initiate a cycle. If the key lever 221 is kept depressed, the cycle will be interrupted by the secondary dog 212 which has become interposed with the retraction of the primary dog 95. However, upon release of the cycling-key lever 221, a spring 225 which acts on the arm 192 restores the train including the primary cycling dog 95 and its rock shaft 96 and concomitantly the secondary dog 212 is retracted. The interrupted cycle is thereby restarted and is concluded when the stud 98 of the clutch mechanism is intercepted by the restored primary dog 95. It will be apparent therefore that continued depression of the cycling-key lever 221 cannot cause an unwanted repetition of a full cycle. Ordinarily the cycling-key lever 221 is depressed and immediately released, this being sufficient to retract the dog 95 and thereby to release the stud 98 which immediately moves under the lock edge 153 of the dog 95; and when, in the ensuing cycle, the stud 98 has passed beyond said edge 153, the dog 95 is immediately restored by means of the spring 225, and concomitantly the secondary dog 212 is retracted so that it does not interrupt the cycle. Similarly the automatic cycling lever 89 is depressed and immediately released by the carriage within a letter-feed step of the latter so that a cycle that is automatically initiated by the carriage is not interrupted by the secondary dog 212.

The electric motor M may be started and stopped concomitantly with starting and stopping a cycle. A switch, Figures 4 and 6 for opening and closing the motor circuit 227 comprises

a contact 228 fixed to an insulator plate 229 mounted on a bracket 230 attached to the framework. Another contact 231 of resilient spring material is also fixed to said plate 229 and is shaped so that it may be cammed and separated from the contact 228 by a suitably insulated cam tappet 232 attached to the clutch-mechanism plate 99. Normally, said tappet 232 keeps the contacts 228, 231 separated as in Figure 6. When a cycle is initiated by retraction of the dog 95 and the cam plate 99 consequently rotates slightly clockwise, the tappet 232 on said plate 99 leaves the spring contact 231 so that the latter springs into contact with the contact 228 thereby closing the circuit and starting the motor. A secondary insulated tappet 233 is disposed on the plate 99 to engage and separate the spring contact 231 from the contact 228 to open the circuit and stop the motor when the cycle is interrupted by means of the secondary dog 212 if the latter should be interposed in effective position as through continued depression of the cycling-key lever 221 or through continued depression of a tabulating-key lever 30. While the cycle is interrupted, the tappet 233 keeps the contacts 228, 231 open; but when the cycle is restarted through retraction of the secondary dog 212, the resultant slightly clockwise rotation of the plate 99 causes the secondary tappet 233 to leave the contact 231 so that the latter springs into contact with the contact 228 again to restart the motor.

Inasmuch as the secondary dog 212 may come into play to interrupt a cycle and open the contacts 228, 231 during a carriage-return operation, the motor circuit in that case is not broken but is sustained by means of the switch contacts 234 that are closable and openable as through the rocking of the carriage-return mechanism shaft 133, the means not shown, for this purpose being exemplified in my Patent No. 2,054,095.

During an uninterrupted cycle, the secondary tappet 233 opens the contacts 228, 231 briefly, said contacts being reclosed immediately due to the continued movement of said tappet 233 through the momentum of the parts.

In the described type of machine, a key 235 and its bar 236, Figure 8, are shiftable rearwardly to condition the machine for a certain function, as, for instance, a function related to a credit balance condition, and coincidentally effect a cycle of the general operator mechanism. A spring, not shown, urges the key bar 236 forwardly and the latter is retained in its rearwardly shifted position by a latch arm 237 on the cycle tripping lever 185. Thus, in passing over the forward latching end of said arm 235, the lever 185 is rocked counterclockwise of Figure 3 to initiate a cycle.

At the beginning of an ordinary cycle, the latch arm 69 may be rocked counterclockwise to drop the plate 68 to disable the control of the computing mechanism by the carriage. Therefore, a roll 239 on the disk 216 may engage an arm of the latch arm 69 at the beginning of a cycle.

Variations may be resorted to within the scope of the invention and portions of the improvements used without others.

What is claimed is:

1. In a machine of the character described having a key movable to an operated position; a cycling mechanism, a dog shiftable from a normal position to initiate an operation of said cycling mechanism, an interlock mechanism for blocking simultaneous operation of said key and a shift of said dog, a shifter for said dog, and a

yieldable operative connection, including a spring, between said shifter and dog whereby said shifter if shifted to operated position, while said key is in operated position and therefore through said interlock mechanism blocks said dog, renders said spring potentially effective for shifting said dog when said key is restored and frees said dog from said interlock mechanism.

2. In a machine of the character described having a key; a reciprocatory actuator, a lock device conditioned substantially concomitantly with reciprocation of said actuator to lock said key, means tending before the end of the return stroke of said actuator to restore said lock device, a block movable to a position to prevent restoration of said lock device, means tending to restore said block, means enabling said actuator in a final portion of its return stroke to pick up and move said block to said position, and means acting at the end of the return stroke of said actuator to release said block for consequent restoration of said block and said lock device.

3. In a machine of the character described having a key; a reciprocatory actuator, a rotary cam operable in a one-revolution cycle concomitantly with forward and return reciprocation of said actuator, a key-lock device actuated and maintained in actuated condition under control of said rotary cam during said revolution, means tending to restore said lock device, said cam during a final part of its revolution leaving said lock device free for restoration, a block movable to a position to prevent restoration of said lock device, means tending to restore said block, means operative coincidentally with a final portion of the return stroke of said actuator to pick up and move said block to said position, and means acting at the end of the return stroke of said actuator to release said block for consequent restoration of said block and lock device.

4. In a machine of the character described having key mechanism, a carriage and mechanism-controls operable by said carriage; the combination of a device conditionable to determine a power driven movement of said carriage, means responsive to the conditioning of said device to disable said controls, a power operable cycling mechanism for restoring said controls, means movable to an operated position in response to the conditioning of said carriage-movement-determining device to determine an operation of said cycling mechanism, and a key-lock mechanism having operative connection to said last-

named means whereby the movement of said last named means to operated position to determine an operation of said cycling mechanism immediately renders said key-lock mechanism effective before said cycling mechanism operation commences.

5. In a machine of the character described having key-mechanism, a power-movable carriage and a machine control operable by said carriage; the combination of a device operable and restorable in accordance with starting and ending, respectively, a power-driven movement of said carriage; means responsive to the operation of said device at the start of a carriage movement to disable said control; a power-operable cycling mechanism effective within a latter portion of its cycle for restoring said control; means movable to an operated position, in response to said operation of said device, to effect and limit operation of said cycling mechanism for the part of a cycle preceding said latter portion, said last-named means becoming restored, at the restoration of said device at the end of the carriage movement, for resulting completion of the cycle; a key-lock having a one way motion-transmitting connection from said last-named means whereby the movement of the latter to operated position moves and renders the key-lock effective, said key-lock tending to become restored, and said one way connection leaving it free to become restored at the restoration of said last-named means; and means cooperative with the cycling mechanism during said latter portion of the cycle to keep the key-lock effective until the cycle has been completed.

6. In a machine of the character described, having key mechanism; the combination with a normally ineffective key lock; general-operator mechanism operable in a cycle; a cam cooperative with the general-operator mechanism for moving the key lock, and then keeping it effective during the major part of the cycle but not during the remainder of the cycle; a block movable to position to keep the key lock effective, said block tending to return from said position; means operated by said general operator mechanism to pick up releasably and move said block to effective position before said remainder of the cycle, and means operated by the general operator mechanism to release the block at the end of the cycle for consequent restoration of said block and the key lock.

HENRY L. PITMAN.
